DISCONNECTING SWITCH

William A. Hillebrand, Akron, Ohio, assignor to
 The Ohio Brass Company, Mansfield, Ohio, a
 corporation of New Jersey

Application March 23, 1932, Serial No. 600,616

2 Claims. (Cl. 200—48)

This invention relates to electric switches such as are used for disconnecting high voltage transmission lines, and has for one of its objects the provision of a switch which will occupy a minimum space and avoid danger of arcing to adjacent structures.

A further object is to provide a switch which can be easily operated in all weather conditions.

Another object is to provide a switch which shall be of improved construction and operation.

Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is a partly diagrammatic elevation showing one embodiment of the present invention.

Fig. 2 is a vertical section of the housing for receiving the switch blade when retracted to open the switch.

Fig. 3 is a horizontal section of a housing for the switch terminal opposite that shown in Fig. 2, the switch contact being shown in elevation.

In the drawing, the numerals 10 and 11 represent post insulators to which are secured the ends of conductors 12 and 13 respectively to be joined by a disconnecting switch. On the insulator post 10 is mounted a housing 14 which may be formed of metal and which is open at the end 15 facing the insulator 11. The insulator 11 carries a housing 16 provided with an open face 17 facing the insulator 10. The housings 14 and 16 may be flared adjacent their open faces, as shown in the drawing, to conduct drip water to the lower portion of the edge of the housing and prevent it from falling across the open face.

40 Mounted on the insulator post 10 within the housing 14 is a bracket 18 which carries a switch blade 19 in the form of lazy tongs. The end arms of the lazy tongs are pivoted on the bracket 18 at the points 19 and 20 and are operated by a screw rod 21 threaded into bearing blocks pivotally mounted in the ends of the arms 22 and 23. At their free ends the lazy tongs carry a contact member 24 arranged to engage contact terminals 25 mounted in the housing 16 on the insulator 11. The contact terminals 25 are flared to guide the plate 24 into place between the terminal members. In order to provide good conductivity, the blade 19 carries a flexible conductor 26 electrically connecting the member 24 with the conductor 12. A spring drum 27 is mounted on the

bracket 18 and automatically winds up the conductor 12 when the blade 19 is folded to its collapsed position within the housing 14. The operating rod 21 is rigidly fixed to the upper end of an insulator stack 28 which is arranged to be rotated by gearing 29, driven by a motor 30. A universal joint 31 is provided at the lower end of the stack 28 to permit lateral swinging movement of the rod 21 caused by the lever arms 22 and 23. A screw 32 is connected to the gearing 29 and carries a traveling nut 33 for controlling the motor 30.

A quick acting reversing lever 34 is operated by the nut 33 and controls two sets of switches 35 and 36 for reversing the motor. The parts are so arranged that when the main switch 19 reaches the end of its travel in either direction, the switches 35 and 36 are reversed by the controller 34. Hand switches 37 and 38 are also provided for controlling the operation of the motor 30. When the parts are in the position shown in Fig. 1 of the drawing, the motor 30 will be stationary since the switches 37 and 38 are both open. If the operator closes the switch 37, the motor will be operated in a direction to open the switch 19.

As soon as the switch 19 reaches its open position shown in Fig. 2, the reversing lever 34 will be suddenly operated by the nut 33 to open the switch 35 and close the switch 36. This will stop the motor since the switch 35 will be open in one motor circuit, and the switch 38 will be open in the other circuit. When the operator wishes to close the main switch 19, he opens the switch 37 and closes the switch 38, which will drive the motor in a direction to close the main switch. As soon as the switch 19 reaches its closed position, the reversing lever 34 will again be operated to open the switch 36 and close the switch 35. It will be impossible for the operator to cause the motor to over-run in either direction since the positions of the switches 35 and 36 are automatically reversed by the lever 34 whenever switch 19 reaches its extreme position. If the operator should inadvertently close both switches 37 and 38 at the same time, the only result would be that the switch 19 will be alternately opened and closed until the operator's attention is drawn to the fact that both switches 37 and 38 are closed. It will then only be necessary for the operator to open one of the control switches to set the main switch in the position that he desires. In fact, the only thing the operator need do is to close the proper switch and open the other whenever he wishes to open or close the main switch, and he

cannot operate his control switches so as to do any damage.

It will be seen that the contact members for the main switch are enclosed at all times in housings which protect them on all sides, except the confronting vertical faces so that the contacts are reasonably well protected from all weather conditions. Should ice or sleet form upon the exposed portion of the blade 19, this will be easily broken when the blade is operated, since the leverage at the joints is the same at the extremity of the switch as it is at the joints closest to the operating mechanism. The switch never moves out of a direct line between the two contacts so that it does not swing toward adjacent objects as is the case with an ordinary pivoted switch. The housings 14 and 16 form electrostatic shields enclosing the terminal members and also the switch blade when the switch is open, thus minimizing corona discharge from the switch parts and consequently preventing radio disturbances.

In order to hold the entering edge of the blade 24 firmly in a vertical position as it enters the contacts 25, limit stops 40 are provided on the blade in a position to engage the projecting ends of the links 41 which connect the contact plate 24 with the lever arms of the lazy tongs 19. When the switch blade has reached the end of its closing movement, the links 41 will engage the pins 40 and hold the contact plate 24 in the position shown in Fig. 1.

I claim:

1. A disconnecting switch for outdoor use comprising a pair of spaced terminals, a switch blade for connecting and disconnecting said terminals and means for protecting said switch blade when said switch is open, said means comprising a housing enclosing one of said terminals and having its maximum dimension materially less than half the length of the spacing between said terminals to provide maximum clearance about the terminal contained therein when said switch is open, said blade comprising a series of links pivoted together to form extensible and collapsible lazy tongs

having one end mounted on the terminal within said housing and having a contact member at the other end thereof adapted to engage the other terminal of said switch, said housing being of a size to conform approximately to said switch blade when collapsed and a rotatable shaft for operating said blade, said shaft having an insulating portion extending away from said housing, a reversible motor for driving said shaft, two sets of connections for operating said motor in opposite directions respectively, a pair of switches for controlling said connections, said switches being interlocked so that one of said switches is open when the other is closed, trip mechanism for reversing said switches when said disconnecting switch reaches the respective limits of its movement, and separately operable hand controlled switches for said respective connections.

2. A disconnecting switch for outdoor use comprising a pair of spaced terminals, a switch blade for connecting and disconnecting said terminals and means for protecting said switch blade when said switch is open, said means comprising a housing enclosing one of said terminals and having its maximum dimension materially less than half the length of the spacing between said terminals to provide maximum clearance about the terminal contained therein when said switch is open, said blade comprising a series of links pivoted together to form extensible and collapsible lazy tongs having one end mounted on the terminal within said housing and having a contact member at the other end thereof adapted to engage the other terminal of said switch, said housing being of a size to conform approximately to said switch blade when collapsed and a rotatable shaft for operating said blade, said shaft having an insulating portion extending away from said housing, a flexible cable carried by said switch blade and connecting the contact member at one end thereof with the terminal member at the other end thereof, and a spring drum for storing said cable when said said switch blade is collapsed.

WILLIAM A. HILLEBRAND.
